GOLF PUTTER

Samuel Lombardo, 3419 Corinna Drive,
Palos Verdes Peninsula, Calif. 90274

Filed Oct. 28, 1968, Ser. No. 14,203

Term of patent 14 years

Int. Cl. D21—03

U.S. Cl. D34—5

FIG.5

FIG. 1 is a left side elevational view of a golf putter showing my new design;

FIG. 2 is a right side elevational view of the golf putter shown in FIG. 1;

FIG. 3 is a rear view of the golf putter shown in FIG. 1;

FIG. 4 is a front view of the golf putter shown in FIG. 1;

FIG. 5 is a top plan view thereof; and
FIG. 6 is a bottom plan view.

I claim:

The ornamental design for a golf putter, substantially as shown.
